UNITED STATES PATENT OFFICE.

CHARLES BARTON HARRIS, OF LONOKE, ARKANSAS, ASSIGNOR TO DANIEL DANIEL, OF SAME PLACE.

GROUND PLOW-STOCK AND COLTER ATTACHMENT.

SPECIFICATION forming part of Letters Patent No. 626,786, dated June 18, 1899.

Application filed October 7, 1898. Serial No. 692,931. (No model.)

To all whom it may concern:

Be it known that I, CHARLES BARTON HARRIS, a citizen of the United States, residing at Lonoke, in the county of Lonoke and State 5 of Arkansas, have invented certain new and useful Improvements in Plows, New-Ground Plow-Stock, and Colter Attachments; and I do declare the following to be a full, clear, and exact description of the invention, such 10 as will enable others skilled in the art to which it appertains to make and use the same, reference being had to the accompanying drawings, and to the figures of reference marked thereon, which form a part of this specification. 15

My invention is a new-ground plow-stock, colter, and colter attachments; and it consists of the novel construction and arrangement of its parts.

In the accompanying drawings, Figure 1 is a part of a plow-stock showing my invention attached thereto. Fig. 2 is a perspective view of a flanged, slotted, and perforated plate. Fig. 3 is a perspective view of the colter-holder, and Fig. 4 is a perspective view of the binder.

My invention is described as follows:

1 is the draw-beam, provided with a perforation or bolt-hole, as indicated by the dotted lines 2, and a mortise-hole, as indicated by the dotted lines 3. To the top of the beam 1 is secured a plate 4, having in its front end a perforation 5 and near its rear end a mortise-slot 6, its rear end turned up, forming 35 a flange 7. To the under face of the draw-beam 1 is secured a colter-holder 8, in the front end of which is a perforation 9, corresponding to the perforation 5 in the plate 4, and near its rear end is a mortise-slot 10, corresponding to the mortise-slot 6 in the plate 4, and on the under side of this colter-holder 8 is a recess or depression 11 for the unbroken part 12 of the binder to rest in.

The binder consists of a U-shaped bolt 45 having threaded ends 13, a plate 14, having perforation for said threaded ends to work through, and nuts 15, working on said thread-

ed ends. A bolt 16 passes tip through perforation 9, perforation represented by the dotted lines 2, and is secured in place by a nut 17. 50

The binder, Fig. 4, has its unbroken part 12 resting in the recess 11. Its arms pass up on each side of the beam 1 and each edge of the plate 4. The plate 4 of the binder is then put on, its rear edge fitting against the 55 front face of the flange 7.

Horizontally passing through the colter-holder 8 and entering the mortise perforation 10 is a threaded perforation 18, and through this perforation works a set-screw 19, its inner end screwing against the shank 20 of the colter 21.

The purpose of this invention is to secure to the farming people such a plow-stock and colter attachment as will stand rough usage 65 in the roughest new grounds. With this colter any sort of a plow-foot may be used, and when the roots are not entirely broken away it may be used in connection with my invention, "Plows and plow-points," filed Oc- 70 tober 7, 1898, Serial No. 692,930.

Having described my invention, what I claim as new, and desire to secure by Letters Patent, is—

In combination with the draw-beam 1 of a 75 plow, having the perforations 2 and 3, the plate 4, provided with perforation 5, mortise-slot 6, and flange 7; the colter-holder 8, provided with a perforation 9, mortise-slot 10, recess 11, threaded perforation 18; bolt 16, passing through perforations 9, 2, and 5, and secured by nut 17; the binder, consisting of the U-shaped part, threaded ends 13, perforated plate 14, and nuts 15; colter 21, its shank end 20, passing through mortise-slot 6, perforation 3, mortise-slot 18, and secured in place by set-screw 19, substantially as shown and described. 85

In testimony whereof I affix my signature in presence of two witnesses.

CHARLES BARTON HARRIS.
